UNITED STATES PATENT OFFICE.

ABE WALRADT, OF CALDWELL, IDAHO.

LEAF-SPRING-BENDING DEVICE.

Application filed May 5, 1922. Serial No. 558,637.

To all whom it may concern:

Be it known that I, ABE WALRADT, a citizen of the United States, and a resident of Caldwell, in the county of Canyon and State of Idaho, have invented a new and useful Improvement in Leaf-Spring-Bending Devices, of which the following is a full, clear, and exact description.

My invention relates to improvements in leaf spring bending devices, and it consists in the combinations, constructions, and arrangements herein described and claimed.

An object of my invention is to provide a leaf spring bending device which is adapted to bend a leaf spring of any size into any curvature desired.

A further object of my invention is to provide a device of the character described which has a novel lever which is adapted to hold the spring bending device in any desired position.

A further object of my invention is to provide a device of the character described which is simple in construction, consists of a minimum number of parts, and which is durable and efficient for the purpose intended.

Other objects and advantages will appear in the following specification, and the novel features of the invention will be particularly pointed out in the appended claim.

My invention is illustrated in the accompanying drawing, forming part of this application, in which

The figure is a perspective view of the device, portions thereof being broken away.

In carrying out my invention, I provide a rectangular box-shaped frame 1 which is preferably made of a plurality of angle iron strips. The angle iron strips are bolted or riveted together in any manner so as to provide a strong and rigid device. A table top 2 is carried by the frame 1 and supports the work 3.

The table top 2 carries a spring holding means which comprises a rod 4, this rod being rigidly supported by brackets 5 which in turn are secured to the frame 1. Spring holding hooks 6 are adjustably secured in brackets 7 and are locked in adjusted position by means of hand screws 8. The brackets 7 are slidably disposed on the rod 4 and are adapted to be moved to any desired distance from the center bracket 5. The hook-shaped members 6 have downwardly turned ends 9 which rest on the top of the table 2,

these ends being adapted to receive the ends of the leaf spring 3.

A leaf spring bending device is carried by the frame 1 and is adapted to bend the spring 3 to any desired curvature. A bar 10 is slidably supported by guide brackets 11 which are carried by the frame 1. It will be observed from the drawings that the bar 10 is disposed beneath the table top 2 and has a centrally raised portion 12 which is disposed adjacent to a slot 13 in the table top 2. A novel means for moving the bar 10 will be hereinafter described.

The bar 10 through the medium of an upright 15 carries a spring engaging bracket 14 which is adapted to engage with the spring and move the latter when the bar 10 is actuated. The bracket 14 is secured to an upright 15 which is carried by the bar 10. A pin 16 adjustably secures the bracket 14 to the upright 15 whereby the bracket 14 may be moved in a vertical direction with respect to the upright 15. The upright 15 projects through the slot 13 and is movable therein. From this construction it will be apparent that when the bar 10 is actuated, it will move the central portion of the spring 3 outwardly with respect to the ends of the spring which are held in fixed position by means of the hooks 6.

The bar 10 is moved by means of a rock-shaft 17. The shaft 17 carries a roller bracket 18, which in turn supports a disk 19. A ring 20 is carried by the disk 19 and is spaced therefrom by ball bearings 21. The outer periphery of the ring 20 is grooved and is received in a U-shaped depending portion 22 which is integral with the rod 10. A rotation of the rock-shaft 17 will swing the bracket 18, which in turn will move the bar 10 in the desired direction. The ring 20 is free to rotate with respect to the disk 19, since it is anti-frictionally mounted on the disk 19 by means of the ball bearings 21. A lever 23 for rotating the rock-shaft 17 is rigidly secured to the outer end of the rock-shaft 17. The shaft 17 is journaled in bearings 24 which are carried by angle irons 25, the latter being secured to the frame 1. The lever 23 is disposed adjacent to an arcuate-shaped member 26 to which it may be secured by means now to be described. A disk 27 is rotatably carried by the lever 23 and is connected to locking members 28 by means of links 29. The members 28 have slots 30 therein which re-

ceive the arcuate-shaped member 26. The members 28 have extensions 31 which are loosely received in eyelets 32, the eyelets being rigidly secured to the lever 23. The 5 upper ends of the extensions 31 are connected to the lever 23 by means of springs 33. The springs 33 tend to swing the upper ends of the members 28 toward each other and to swing the lower ends of the 10 member 28 away from each other so as to cause the sides of the slots 30 to grip the arcuate member 26 and to hold the lever 23 in adjusted position. The members 28 fulcrum about the eyelets 32 as a pivot. A 15 releasing handle 34 is pivotally carried by the lever 23 and is connected by means of a rod 35 to the disk 27. When the handle 34 is swung towards the lever 23, it rotates the disk 27 so as to swing the lower ends of 20 the members 28 towards each other which releases the member 28 from the arcuate member 26 and permits the lever 23 to be swung.

From the foregoing description of the 25 various parts of the device, the operation thereof may be readily understood. In bending a spring 3 into the desired shape, the hooks 6 are first moved on the rod 4 so as to dispose the hooks at the end of the spring. 30 The spring 3 is heated until it gets red hot and is then placed upon the table so that the ends thereof are retained by the downwardly bent portions 9 of the hooks 6. The lever 23 is then released from the member 35 26 by moving the handle 34 and is swung so as to move the bracket 14 into engagement with the spring 3. The lever 23 can be swung to any angle desired and be instantly held in adjusted position by means 40 of the members 28. It is obvious that as

the lever 23 is swung, it will move the bracket 14 so as to bend the spring 3 into the desired shape. The spring 3 is left to cool after being bent into the desired shape and is then released from the device by 45 actuating the lever 23 so as to bring the bracket 14 back towards the center of the table 2. In like manner, any number of leaves may be added to the spring 3, or a new leaf may be added to an old spring. 50

The device is very simple in construction and requires but two operations to bend a spring into the desired shape. The brackets 6 are quickly adjustable so as to engage with the ends of a spring of any length, thereby 55 providing a device which is adapted to bend a spring of any desired length. The mechanism actuated by the lever 23 is adapted to engage with the middle of the spring so as to bend it into the desired shape. The 60 locking members 28 are so constructed that they will instantly engage with the member 26 and rigidly hold the lever 23 in adjusted position. The device is very simple in construction and is efficient for the purpose intended. 65

I claim:

A spring bending device comprising a frame, means carried by said frame for engaging with the end of a spring, means for engaging with the middle of the spring for bending the latter, said means comprising a bar slidably carried by said frame, a frame rigidly secured to said bar, a shaft, means for actuating said shaft, an arm carried by 70 said shaft, and a ball bearing race connecting the free end of said arm to said 75 second named frame.

ABE WALRADT.
